CLAIM

The ornamental design for a die for gum forming as shown and described.

DESCRIPTION

FIG. 1 is an upper, front, right-side perspective view of a die for gum forming, showing the new design;
FIG. 2 is a front view of the die for gum forming;
FIG. 3 is a lower, front, left-side perspective view of the die for gum forming;
FIG. 4 is a lower, front, right-side perspective view of the die for gum forming;
FIG. 5 is an upper, front perspective view of the die for gum forming;
FIG. 6 is a back view of the die for gum forming;
FIG. 7 is a top view of the die for gum forming;
FIG. 8 is a bottom view of the die for gum forming;
FIG. 9 is a left-side view of the die for gum forming;
FIG. 10 is a right-side view of the die for gum forming;
FIG. 11 is a magnified view (as shown in FIG. 1) of the die for gum forming;
FIG. 12 is a vertical cross-sectional view (as shown in FIG. 2) of the die for gum forming; and,
FIG. 13 is a vertical cross-sectional view (as shown in FIG. 9) of the die for gum forming.

The dash-dot-dash lines represent boundary lines for the claimed design, where features inside the dash-dot-dash lines form no part of the claimed design.
